UNITED STATES PATENT OFFICE

2,169,153

COMBINED BEER COOLING AND DISPENSING APPARATUS

William Kissinger, Kiel, Wis.

Application November 1, 1937, Serial No. 172,281

1 Claim. (Cl. 62—141)

This invention relates to a combined beer cooling and dispensing apparatus and has for its object to maintain the beer at a constant temperature from the time it leaves the keg until 5 it leaves a dispensing faucet ready to drink.

A further object of the invention is to provide, in a manner as hereinafter set forth, an apparatus for the purpose referred to whereby the beer conducting line from the keg to the dispensing faucet is set up without a series of coils.

A further object of the invention is to provide, in a manner as hereinafter set forth, an apparatus for the purpose referred to whereby the beer conducting line is permanently cooled, 15 at a constant temperature without the use of an ice pack therefor.

A further object of the invention is to provide, in a manner as hereinafter set forth, an apparatus for the purpose referred to including an 20 insulated refrigerated storage room, chamber or receptacle for the beer and a portion of the beer conducting line, an insulated refrigerated tubular column for the remaining portion of the beer conducting line and with the column 25 closed at its upper end and opening at its lower end into said room, chamber or receptacle.

Further objects of the invention are to provide, in a manner as hereinafter set forth, an apparatus for the purpose referred to which is 30 simple in its construction and arrangement, strong, durable, compact, thoroughly efficient in its use, readily assembled and installed relative to a bar counter, and comparatively inexpensive to set up.

To the above ends essentially and to others which may hereinafter appear, the invention consists of the novel construction, combination and arrangement of parts as will be more specifically referred to and illustrated in the accompanying drawing wherein is shown an embodiment of the invention, but it is to be understood that changes, variations and modifications may be resorted to which fall within the scope of the invention as claimed.

45 In the drawing:

Figure 1 is a longitudinal section of the apparatus illustrating the adaptation thereof with respect to a bar or counter,

Figure 2 is a transverse section of the apparatus installed with respect to the bar or counter, and

Figure 3 is an enlarged detailed view showing the connection between the bar or counter drain and a drainage lead-off.

55 With reference to the drawing, I generally

indicates a bar or counter including an upstanding front portion 2 and a horizontally disposed counter portion 3 extending inwardly at right angles to the portion 2 in proximity to the upper end of the latter. The inner face of portion 2 5 is suitably connected with the outer lengthwise edge of the portion 3. The latter in proximity to its rear lengthwise edge 4 is formed with a vertically disposed narrow strip 5 having its lower lengthwise edge providing an abutment 10 for a purpose to be referred to. The portion 3 intermediate its ends and in proximity to its edge 4 is formed with an opening 6. The part of portion 3 bordering the upper end of opening 6 is rabbeted as at 7. Arranged within the 15 rabbet 7 is a perforated drain plate 8. Removably mounted in the portion 3, extending through opening 6, and abutting the strip 5 is an open top drainage collector provided at its top with a flange 10 for seating in rabbet 7 below and 20 bearing against plate 8. The bottom 11 of collector 9 is formed with an opening 12. The collector 9 is of less height than strip 5. The portion 2 of bar 1 is anchored to the floor 13 of the room in which the bar is set up. The floor 13 25 is formed with an opening 14 aligning with the collector 10. The opening 14 may be of any suitable contour, preferably rectangular and is so shown.

The apparatus includes a refrigerated storage 30 room, chamber or receptacle in which the keg or kegs of beer is or are stored under a state of refrigeration and such part of the apparatus will be termed a receptacle generally indicated at 15. The receptacle may be of any suitable 35 contour preferably square and is so shown. The receptacle 15 includes an outer section 16 preferably of sheet metal, an inner section 17 preferably of sheet metal and an intermediate section 18 formed of insulating material in the form 40 of a compact body of greater thickness than the sections 16, 17. The receptacle includes a top wall, a bottom, a front wall, a rear wall and a pair of side walls indicated at 19, 20, 21, 22, 23 and 24 respectively, provided by the sections 16, 45 17 and 18.

The top portions of the sections 16, 17, 18 are cut out to form the top wall with an opening 25 preferably of rectangular contour. The cutout in sections 17 and 18 are of less area than the 50 cutout in section 16. The portions of the sections 16, 17 and 18 which provide the side wall 22 are so formed to provide a door frame 26 in which is normally arranged a hinged door 27 whereby access may be had to the chamber 27a 55

provided by the receptacle 15. The door 21 is constructed of materials corresponding to and arranged in a manner similar to the walls of the receptacle. The latter is normally closed to the atmosphere.

The apparatus includes a closed top and open bottom hollow column 28 of the contour corresponding to the opening 25. The column 28 is formed of outer and inner metallic sections 29, 30 and an intermediate section 31 of insulated material of greater thickness than the other sections. The said sections are so formed to provide the column 28 with top, front, rear and a pair of side walls 32, 33, 34, 35, 36 respectively. The section 29, of the column at its lower end is connected to the edge of the cutout of the outer section 16 of the wall 19. The section 30 of the column at its lower end is connected to the edge of the cutout of the inner section 17 of the wall 19 and bears against the edge of the cutout of the intermediate section 18 of the wall 19. The intermediate section 31 of the column at its lower end bears against the intermediate section 18 of the wall 19. The sections 29, 30 of the wall 32 of the column in proximity to the top wall 32 are formed with two spaced parallel pairs of aligning openings 37. The section 29 of the wall 32 of the column is provided with an opening 38 in proximity to the section 29 of the wall 33 of the column.

Arranged within the intermediate sections of the walls 32, 33 is a drainage conducting-off pipe 39 having a funnel-shaped upper end 40 into which extends a drain pipe 41 which at its upper end is secured in the opening 12 in the bottom of the collector 9. The pipe 41 passes through the opening 38. The pipe 39 has an outwardly directed downwardly inclined lower part 42 which is secured in an opening 43 formed in the section 29 of wall 33 in the opening 37.

The pipe 39 discharges into an open top and closed bottom receptacle 44 secured to the outer face of and below the front opening 37 in wall 33 of the column and extends to a point in proximity to floor 13. The body of receptacle 44 is open at its back, but when secured to wall 33, it is closed by the latter. The receptacle 44 in proximity to its upper end and below opening 43 has secured therein a perforated partition 45 which inclines downwardly from rear to front. The receptacle 44 has its front disposed at a rearward inclination from partition 45 to its bottom 46. The latter has connected thereto a discharge pipe 47 which extends downwardly through the bottom 13. The receptacle 44 is common to the collector 9 and one or more dispensing faucets 48.

The apparatus includes an intermittently operable thermostatically controlled refrigerating structure 49 common to and for refrigerating the chamber 27^a and the space 50 provided respectively by the receptacle 15 and column 28. The space 50 at its lower end opens into the upper end of chamber 27^a. The thermostat for the structure 49 is of the electrical type, indicated at 51, arranged within chamber 27^a and secured to the lower face of the top wall 19 of the receptacle 15. The circuit connections between thermostat 51 and the mechanism 49 is indicated at 52. The structure 49 includes a coil element 53 positioned against the inner face of and extended through the wall 23 of receptacle 15.

Within the chamber 27^a and supported upon the bottom of receptacle 15 are shown kegs of

beer, by way of example, two in number and designated 54, 55 and extending upwardly from these latter are beer conducting or dispensing lines 56, 57 respectively. The major portion 58 of the length of each line is straight, vertically disposed and arranged in chamber 27^a and space 50. The remaining portion 59 of the length of each line is of materially less length than and disposed outwardly at right angles to the upper end of portion 58. The portion 59 of line 56 extends through one of the pairs of aligned openings 37 and is connected to a faucet 48. The remaining portion 59 of the line 57 extends through the other pair of aligned openings 37 and is connected to a faucet 48. If desired the lines 56, 57 may be enclosed throughout with insulating material.

When the apparatus is arranged relative to the bar 1 the column 28 is positioned below and spaced from collector 9 and abuts the strip 5. The receptacle 15 is suitably supported below the floor 13 and the column 28 is of a length to extend through opening 14 to receptacle 15.

The element or receptacle 15 provides what may be termed a normally closed insulated structure providing a chamber for the storage of a barrel or keg of beer and for housing a portion of the length of a beer dispensing line leading from the keg. The element or column 28 provides what may be termed a closed top insulated hollow structure of column-like form which opens at its bottom into the storage chamber and provides a passage for housing another portion of the dispensing line. The column 28 is formed with aligned openings for the passage of the remaining portion of the dispensing line to a faucet. The arrangement of the dispensing line relative to the refrigerated chamber and space with the controllable refrigerating structure will provide for the maintaining of the beer at a constant temperature as it travels through the line from the keg or barrel to the faucet.

What I claim is:

In a combined beer cooling and dispensing apparatus, an insulated refrigerated closed upstanding hollow structure for positioning under and for extension to a point in proximity to a beer dispensing counter and for storing and refrigerating a beer source, a beer drainage collector arranged over the top of said structure and disposed in collecting relation with respect to the counter, said collector including a depending drain nipple arranged over the top of said structure, a refrigerated beer dispensing line leading from said source including an angularly disposed upper end terminal portion extending outwardly through the upper portion of a side of said structure and adapted to open in a faucet, an upstanding drainage conducting off pipe embedded in said side and top, extending upwardly from said top and having its upper end encompassing said drain nipple, the lower end of the conducting off pipe opening at the front of said side below the said terminal portion, means cooperating with the front of said side to provide a laterally extended open top and closed bottom receptacle into which, below the top thereof said conducting off pipe discharges, a perforated partition within said receptacle below the lower end of the conducting off pipe, and a discharge pipe leading from the bottom of the receptacle.
